(57) **CLAIM**

The ornamental design for faucet spout, as shown and described.

DESCRIPTION

FIG. 1 is a front perspective view of the faucet spout, showing our new design.

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines showing various elements of the faucet spout and the faucet handles are included for the purpose of illustrating non-claimed subject matter and form no part of the claimed design.
